(57) **CLAIM**

We claim the ornamental design for a wash place unit with illumination, as shown and described.

DESCRIPTION

FIG. 1 is a perspective view of a wash place unit with illumination showing our new design in a non-illuminated state.

FIG. 2 is another perspective view of the wash place unit of FIG. 1 showing the wash place unit in a first illuminated state.

FIG. 3 is a perspective view of the wash place unit with illumination having a different bottom and showing the new design in the non-illuminated state.

FIG. 4 is another perspective view of the wash place unit of FIG. 3 and showing the wash place unit in the first illuminated state.

FIGS. 5-8 are perspective views showing the wash place unit of FIG. 1 in a sequence from the first illumination state to a second illuminated state, a third illuminated state and a fourth illuminated state, respectively.

FIG. 5 is a perspective view of the wash place unit of FIG. 1 in a sequence showing the first illuminated state.

FIG. 6 is a perspective view of the wash place unit of FIG. 1 in a sequence showing the second illuminated state.

FIG. 7 is a perspective view of the wash place unit of FIG. 1 in a sequence showing the third illuminated state.

FIG. 8 is a perspective view of the wash place unit of FIG. 1 in a sequence showing the fourth illuminated state.

FIG. 9 is a perspective view of the wash place unit of FIG. 3 in a sequence showing the first illuminated state.

FIG. 10 is a perspective view of the wash place unit of FIG. 3 in a sequence showing the second illuminated state.

FIG. 11 is a perspective view of the wash place unit of FIG. 3 in a sequence showing the third illuminated state; and,

(Continued)

FIG. 12 is a perspective view of the wash place unit of FIG. 3 in a sequence showing the fourth illuminated state.
